CLAIM

The ornamental design for a fuel tank isolation valve, as shown and described herein.

DESCRIPTION

FIG. 1 is a right side view of a fuel tank isolation valve in accordance with the present disclosure.

FIG. 2 is a left side view of the fuel tank isolation valve of FIG. 1.

FIG. 3 is a top view of the fuel tank isolation valve of FIG. 1. FIG. 4 is a bottom view of the fuel tank isolation valve of FIG. 1.

FIG. 5 is a front view of the fuel tank isolation valve of FIG. 1.

FIG. 6 is a rear view of the fuel tank isolation valve of FIG. 1.

FIG. 7 is a top right rear perspective view of the fuel tank isolation valve of FIG. 1; and,

FIG. 8 is a bottom left front perspective view of the fuel tank isolation valve of FIG. 1.

The broken lines showing portions of the fuel tank isolation valve form no part of the claimed design.
